[57] CLAIM

The ornamental design for an electrical outlet strip, as shown and described.

DESCRIPTION

FIG. 1 is a perspective view of an electrical outlet strip showing my new design;
FIG. 2 is a top plan view thereof;
FIG. 3 is a front elevational view thereof;
FIG. 4 is a rear elevational view thereof;
FIG. 5 is a right end elevational view thereof;
FIG. 6 is a left end elevational view thereof;
FIG. 7 is a top plan view of an electrical outlet strip showing a second embodiment of my new design;
FIG. 8 is a front elevational view thereof;
FIG. 9 is a rear elevational view thereof;
FIG. 10 is a left end elevational view thereof;
FIG. 11 is a right end elevational view thereof;
The broken line showing in FIGS. 7, 10 and 11 is included for the purpose of illustrating environmental elements only and forms no part of the claimed design.
